UNITED STATES PATENT OFFICE.

HARRY LEWIS AND CLYDE H. PETTEY, OF SIOUX CITY, IOWA.

LATCH-CONTROLLING MECHANISM.

1,405,236.

Specification of Letters Patent.

Patented Jan. 31, 1922.

Application filed June 7, 1920. Serial No. 387,247.

To all whom it may concern:

Be it known that we, HARRY LEWIS and CLYDE H. PETTEY, citizens of the United States, and residents of Sioux City, in the county of Woodbury and State of Iowa, have invented new and useful Improvements in Latch-Controlling Mechanism, of which the following is a specification.

A duty of merchant police and night watchmen is to try the doors, at regular intervals, of the establishments under their protection to ascertain if the doors are locked. This is a duty which is very easily and often shirked.

Many devices have been presented and used with varying success for checking the watchmen's calls, but no means, as far as we are aware, has ever been devised which indicates in any way whether or not the doors have been tried.

Our present invention, therefore, has for its primary object the production of a mechanism by which the watchman registers his call and the operation of which requires, first, trying the door to determine whether or not it is unlocked.

Furthermore, the invention contemplates a combination door-latch and register controlling mechanism simple and comparatively inexpensive in construction, yet dependable and thoroughly efficient in operation. The above and other objects and advantages we successfully attain in the embodiments hereinafter described, more particularly defined in the claims and illustrated in the accompanying drawings which form a part of this application and in which like characters of reference indicate corresponding parts throughout the several views, of which:

Fig. 1 is an elevation, partly in section, of a device constructed in accordance with our invention, and as applied to a swinging closure.

Fig. 2 is a vertical section, taken on the line 2—2 of Fig. 1.

Fig. 3 is an enlarged fragmentary front elevation of the same, showing the stop latch, and Fig. 4 is an enlarged perspective view of the stop-latch. Fig. 5 is an elevation of the device partly in section as applied to a closure swinging oppositely to that shown in Fig. 1.

We have illustrated and hereinafter described forms of the invention embodying rotating latch controlling means, yet we

would not be limited to such specific structures, for it will be clear, as the description progresses, that the broad principle of the invention may be associated with divers other types of latch controlling members, and many modifications and alterations may be made in the details of construction and arrangement of parts herein disclosed without departing from the spirit and scope of the invention as defined in the appended claims.

Referring now more particularly to Figs. 1 and 2, 4 represents a door mounted to swing inwardly and provided with a familiar form of lock, 5, including a latch-bolt, 6, and a lock-bolt 7. The latch-bolt is controlled by the usual rotating stem, 8, which, however, is mounted for longitudinal movement, as will presently be made more clear.

On the inner face of the door we mount a casing, preferably including front and rear walls, 9 and 10, respectively, side walls, 11, and top and bottom walls, 12. Within the casing and on the back wall thereof we mount a clock casing, 13, enclosing a suitable clock train (not shown) and an hour spindle, 14, carrying a disc, 15, which, it will be understood, makes a complete revolution daily, weekly, or in any other interval chosen by the manufacturer.

Against the disc, 15, is placed coaxially a second disc, 16, of penetrable material and held removably in place by a washer, 17, and a nut, 18, threaded on the hour spindle, 14. The disc, 16, is preferably provided with graduations, 19, or other characters, dividing the said disc into units or intervals of time. The wall, 10, of the casing may be provided with a door, 20, to afford access to the interior for the application and removal of the discs, 16, to and from the clock.

On the wall, 10, is mounted an inwardly extending bracket, 21, having depending parts, 22, through which reciprocates a horizontal plunger, 23, having a pointed end, 24, to penetrate the disc, 16, the disc, 15, being provided with an annular groove, 25, to permit such penetration. The plunger, 23, is held yieldably from the disc by means of a compression spring, 26, interposed between one of the members, 22, and a stop, 27, carried by the plunger.

The stem, 8, is mounted as usual, to be rotated a determinate distance to withdraw the latch bolt from its keeper, but is also

arranged to move longitudinally through the lock. The stem, 8, is flat-sided, as usual, and projects through the wall, 10, of the casing, and enters the shank, 28, of the 5 inner door-knob, 29, the said shank having a flat-sided interior to slidably receive the stem, but prevent relative rotation between the knob and stem, the knob being rotatably supported, as at 30, on the wall, 10. The 10 outer knob, 31, is fixed to the stem as usual, and between the shank, 32 thereof and the door is interposed a compression spring, 33, which holds the stem, normally, yieldably outward.

15 Within the casing is a guide plate, 34, having a key-hole slot, 35, through the larger portion of which passes the stem, 8, the said plate being supported in spaced relation to the wall, 9, by laterally bent end portions, 20 36, suitably secured to the said wall.

Between the wall, 9, and plate, 34, the stem is provided with a tappet or a lateral lug 37, adapted to pass through the smaller portion of the slot, 35, by forcing the stem 25 longitudinally, after it has rotated, to withdraw the latch bolt from its keeper and align the lug with the said smaller portion of the slot, 35.

On one side wall, 11, of the casing is 30 mounted a suitable bearing, 38, on which is fulcrumed, as at 39, a lever, 40, one end of which is bifurcated to receive the plunger, 23, and engage the cross-pin, 41, in the plunger. The opposite end of the said lever 35 is aligned with the smaller portion of the slot, 35, for engagement by the lug, 37.

By virtue of the construction now disclosed, it is clear that a watchman first rotates the stem in a direction which will unlatch the door, then forces inwardly on the 40 door-knob whereupon the lug, 37, coacts with the lever, 40, and this with plunger, 23, to register the call on the disc, 16, but should the door be unlocked—in other 45 words, should the lock-bolt, 7, not be engaged in its keeper, an attempt to force the stem inwardly will open the door.

On opposite sides of the narrower portion 50 of the slot, 35, are provided guide members, 43, which prevent rotation of the stem after the lug, 37, has been forced into engagement with the lever. Obviously, when the pressure is removed from the knob, 31, the spring, 33, retracts the stem, and subsequently the usual latch-spring (not shown) restores the stem and latch bolt to their 55 normal positions.

As it is not desired to have the device operate during the day or, perhaps, other 60 times, we have provided means for rendering the register inoperable, which may consist of a latch-plate, 45, mounted on the interior of the wall, 10, to slide transversely of the stem, and having a key-hole slot, 46, 65 through which the stem passes and through

the larger portion of which it is free to reciprocate. The stem is provided with an annular groove, 47, which is aligned with the plate, 45, normally, and when the plate is so slid that the grooved portion of the 70 same is disposed within the narrower portion of the slot, 46, obviously, longitudinal movement of the same is prevented.

The plate is provided with an operating lug, 48, projecting through a slot, 49, in the 75 wall, 10.

The embodiment presented in Fig. 5, designed for doors which swing outwardly, differs from the previously described form in that the stem is held yieldably inwardly 80 as by a compression spring, 50, interposed between the wall, 9, and a suitable stop, 51, on the stem. The guide member, 34, is positioned on the wall, 10, and in spaced relation to the latch plate, 45, the lug, 37, being 85 disposed between the said plates. The plunger, 23, carries a fixed, depending arm, 52, positioned for engagement by the lug, 37, and between which and one of the members, 22, is interposed a compression spring, 26, 90 which serves to retract the plunger. In this form the watchman, in rotating the stem sufficiently to withdraw the latch-bolt, 6, from its keeper, aligns the lug, 37, with the arm, 52, then by pulling outwardly from the knob the lug, 37, and arm, 52, coact to register on the dial, providing the door is locked, but in the event the lock-bolt, 7, is not in its keeper, then outward movement of the knob will, obviously, open the door. 100

Having thus described our invention, what we claim as new and desire to secure by Letters Patent of the United States is:

1. In a device of the class described, a latch-bolt, registering mechanism, and means 105 movable to one position to unlatch the latch-bolt, and, subsequently, to another position to operate said mechanism.
2. In a device of the class described, a latch-bolt, registering mechanism and means 110 movable in one direction to unlatch the latch-bolt and subsequently in another direction to operate said mechanism.
3. A registering device for a closure movable to opened and closed positions, including a suitable support adapted to be mounted on the closure, a latch-bolt for releasably preventing opening of the closure, registering mechanism, and means for releasing the latch-bolt and movable in the general 115 direction the closure moves to open to operate said mechanism, whereby the closure, if unobstructed, will be opened when said means is moved in the direction to operate said mechanism. 120

4. A registering device for a closure, movable to opened and closed positions, including a suitable support adapted to be mounted on the closure, a latch-bolt for releasably preventing opening of the clos- 125

- ure, registering mechanism and means movable in a direction different from that in which the closure moves to open to release the latch-bolt, and movable in the general direction the closure moves to open to operate said mechanism, whereby the closure, if unobstructed, will be opened when said means is moved in the direction to operate said mechanism.
- 5 10 5. A registering device for a closure, movable to opened and closed positions, including a suitable support adapted to be mounted on the closure, a latch-bolt for releasably preventing opening of the closure, registering mechanism and means movable in a direction different from that in which the closure moves to open to release the latch-bolt, and subsequently movable in the general direction the closure moves to open to operate said mechanism, whereby the closure, if unobstructed, will be opened when said means is moved in the direction to operate said mechanism.
- 15 20 6. A registering device for a closure movable to opened and closed positions, including a suitable support adapted to be mounted on the closure, a latch-bolt for releasably preventing opening of the closure, registering mechanism, and a member rotatable to release the latch-bolt and movable longitudinally after releasing the latch-bolt and in the direction the closure opens, to operate said mechanism, whereby the closure, if unobstructed, will be opened when said member is moved in the direction to operate said mechanism.
- 25 30 7. A registering device for a closure movable to opened and closed positions, including a suitable support adapted to be mounted on the closure, a latch-bolt for releasably preventing opening of the closure, registering mechanism, and a member rotatable to release the latch-bolt and movable after releasing the latch-bolt in the general direction the closure moves to open to operate said mechanism, whereby the closure will be opened, if unobstructed, when said member is moved in the direction to operate said mechanism.
- 35 40 50 8. A registering device for a closure movable to opened and closed positions, including a suitable support adapted to be mounted on the closure, a latch-bolt for releasably preventing opening of the closure, registering mechanism, and a member rotatable a distance in one direction to release the latch-bolt, and after releasing the latch-bolt yieldable longitudinally to operate said mechanism, whereby the closure, if unobstructed, will be opened when said member is moved longitudinally.
- 45 55 60 9. A registering lock for a closure movable to opened and closed positions, including a casing adapted to be carried by the closure, a lock-bolt carried by the casing adapted to be extended to prevent opening of the closure, a latch-bolt carried by the casing to releasably prevent opening of the closure, registering mechanism, and means operable to release the latch-bolt, and subsequently movable in the direction the closure moves to open, to actuate said mechanism whereby the closure will be opened if the lock-bolt is not extended.
- 70 75 10. A registering lock for a closure movable to opened and closed positions, including a casing adapted to be carried by the closure, a lock-bolt carried by the casing adapted to be extended to prevent opening of the closure, a latch-bolt carried by the casing to releasably prevent opening of the closure, registering mechanism, and operating means for the closure including means for releasing the latch-bolt and means movable in the direction the closure opens, to operate said mechanism, whereby the closure will be opened if the lock-bolt is not extended.
- 80 85 90 11. A registering lock for a swinging closure, including a casing adapted to be secured to the closure, a lock-bolt carried by the casing adapted to be extended to prevent swinging of the closure, a latch-bolt carried by the casing to releasably prevent swinging of the closure, registering mechanism, and means operable to release the latch-bolt and subsequently movable in the direction the closure swings open, to actuate said mechanism, whereby the closure will be swung open if the lock-bolt is not extended.

latch-bolt releasably preventing swinging the closure open, a registering mechanism and means movable to release the latch-bolt and subsequently actuate said mechanism and swing the closure open when the lock-bolt is not extended.

16. The combination with a swinging closure and a lock thereon, including an extensible lock-bolt and a latch-bolt for releasably preventing swinging of the closure, of registering mechanism, and an operating device movable in one direction to release the latch-bolt, and subsequently in another direction to actuate said mechanism and swing closure open if the lock-bolt is not extended.

17. The combination with a swinging closure and a lock thereon, including an extensible lock-bolt and a latch-bolt for releasably preventing swinging of the closure, of registering mechanism and a controlling stem 20 rotatable to release the latch-bolt and subsequently movable longitudinally in the direction the closure swings open, to actuate said mechanism, whereby the closure will be opened if the lock-bolt is not extended. 25

In testimony whereof, we have hereunto set our hands this 24th day of May, 1920.

HARRY LEWIS.
CLYDE H. PETTEY.
